INVENTOR

UNITED STATES PATENT OFFICE.

JOHN A. MUNDY, OF SYRACUSE, NEW YORK, ASSIGNOR TO THE SMITH & GRIGGS MANUFACTURING COMPANY, OF WATERBURY, CONNECTICUT.

LEVER-BUCKLE.

SPECIFICATION forming part of Letters Patent No. 309,730, dated December 23, 1884.

Application filed July 14, 1884. (No model.)

To all whom it may concern:

Be it known that I, JOHN A. MUNDY, of Syracuse, Onondaga county, State of New York, have invented certain new and useful 5 Improvements in Lever-Buckles, of which the following is a specification, reference being had to the accompanying drawings, in which—

- Figure 1 is a top or plan view and an elevation, partly in section, of the buckle closed. 10 Fig. 2 shows a plan view and side elevation of the finger-lever; Fig. 3, like views of the upper body-plate; Fig. 4, like views of the lower body-plate, and Fig. 5 a side elevation of the buckle partly open.
- 15 My invention relates to the class of lever-buckles that are operated by a spring-seated finger-lever, and which are used in combination with a looped adjustable draw-plate to produce tension of fastening.
- 20 It consists of the several devices and combinations of elements hereinafter specifically set forth in the claims.

It is constructed as follows: A is the finger-lever, constructed of sheet metal and struck 25 up to about the shape shown in the drawings, except that at first the barrel *a* is left partly open, to be closed, as hereinafter explained. Upon each side of this lever I construct an 30 outwardly-projecting ear or spur, *b*, (shown in the drawings as rectangular;) but the shape can be varied.

The body proper of the buckle is made in two parts—an upper plate, *B*, and a lower one, *C*—either or both of which may be constructed from springy sheet metal, and when 35 one is formed of such metal the other may be made from ordinary stiff metal. The plate *B* is usually of about the form shown in the drawings, having a rearward tang, in which I 40 punch a rivet-hole, *c*, and having front arms, *d*, one on each side, inclosing the space *y* on three sides. The plate *C* is of about the form shown in the drawings, with a rearward tang, in which I also punch a rivet-hole, and the 45 front arms, *e*, of which plate are connected by the cross-bar *h*, which bar may be integral with the arms *e*, or secured to them in any ordinary manner, the arms and bar wholly inclosing the space *x*. The strap by which the 50 body of the buckle is attached to the shoe

passes through the spaces *x* *y* and covers the tangs of the plates. The rivet-holes in the plates should coincide when the plates are placed upon each other, so that they can be riveted together in their proper relative positions.

55 I connect the finger-lever *A* to the plate *C* by closing the barrel *a* around the bar *h* loosely, with the ears *b* lying under the arms *d* of the plate *B*.

60 *D* is the slotted draw-plate, constructed in the usual manner, with side bars, *m*, connected by cross-bars *o*, the slots freely receiving the lever *A*.

The buckle is operated as follows: I connect the body of the buckle to its holding-strap in the ordinary manner by passing the end of the strap through the spaces *x* *y* in the plates *B* *C*, and bend the end back, so as to inclose the tangs of the plates, and secure it. 70 I then connect the draw-plate *D* to an opposite strap in any ordinary way. I then pass the finger-lever *A* through one of the slots in the plate *D*, the lever being thrown forward for that purpose, and when the lever is next 75 thrown back the ears *b* soon begin to wedge between the plates *B* *C*, and as the movement of the lever backward continues the cam action of the ears springs the plates farther apart until the center of the movement of said 80 ears is reached, when, as the movement of the lever continues, the spring action of the plates will throw the lever down to and hold it in the position shown in Fig. 1, at the same time drawing the plate *D* over and tightening the 85 straps to the desired tension. By this construction of a double-plate body I obtain therein the desired spring action without using any inserted flat or coil spring. The plates *B* *C* can be punched out in one piece and their 90 ends then bent over upon each other.

What I claim as my invention, and desire to secure by Letters Patent, is—

1. A lever-buckle consisting of two superimposed plates, one provided with arms *d*, 95 and the other with a bar, *h*, and a finger-lever connected to one plate, so as to swing thereon, and having spurs *b*, that bear upon the opposite plate, substantially as described.

2. A lever-buckle constructed with the le- 100

ver A, provided with barrel *a* and spurs *b*, the plate B, provided with arms *d*, and the plate C, provided with arms *e* and cross-bar *h*, said plates having the strap-receiving recesses *y* *x*, the 5 parts being connected and operating substantially as and for the purposes specified.

3. A lever-buckle constructed with the lever A, provided with barrel *a* and spurs *b*, the plate B, provided with arms *d*, the plate C, 10 provided with arms *e* and cross-bar *h*, and the

slotted draw-plate D, all connected and operating together substantially as and for the purposes specified.

In witness whereof I have hereunto set my hand this 2d day of July, 1884.

JOHN A. MUNDY.

In presence of—

C. W. SMITH,

W. S. SOPER.
